UNITED STATES PATENT OFFICE.

ALBERT B. CLISSON, OF SYRACUSE, NEW YORK, ASSIGNOR, BY MESNE ASSIGNMENTS, TO THE PROSPERITY COMPANY, INC., OF SYRACUSE, NEW YORK, A CORPORATION OF NEW YORK.

PRESSING-MACHINE MECHANISM.

Application filed June 12, 1924. Serial No. 719,693.

This invention relates to pressing machines, such as garment and laundry pressing machines, and has for its object a particularly simple and efficient mechanism for actuating the movable press head, by which the power can be effectively applied to the press head only when the press head is moved by the operator a predetermined distance toward closed position and preferably when the press head is so close to the buck that it is impossible for the operator to have his hands between the pressing elements, and by which at all other times except when the press head is in nearly closed position or what is termed a safety-first position, the power if applied will idle the motion transmitting mechanism and will be ineffective on the movable pressing element or head.

The invention consists in the novel features and in the combinations and constructions hereinafter set forth and described.

In describing this invention reference is had to the accompanying drawings in which like characters designate corresponding parts in all the views.

Figure 1 is a side elevation of a pressing machine embodying my invention, the press head being shown as in closed position.

Figure 2 is an enlarged fragmentary elevation showing the position of the parts when the press head is open, the position of the links and parts operated thereby when in nearly closed position being indicated in dotted lines.

Figure 3 is a sectional view on line 3—3, Fig. 2.

This pressing machine comprises, generally, cooperating pressing elements as a lower buck 1, and a press head 2, movable toward and from the buck 1, a power member, and actuating mechanism for applying power to the press head after it has been moved preliminarily to what, for convenience, is called a safety first position. The press head is movable preliminarily to a closed position or a nearly closed position, that is a safety first position independently of the power member.

The actuating mechanism comprises toggle members one of which is pivotally connected to the movable head and the other to the frame, these toggle members being normally in folded position and movable toward straightened position by the preliminary movement of the press head 2, inde-

pendently of the power member. Such mechanism further includes connections between the power member and the toggle for straightening the toggle to apply pressure only after the press head has been first moved to a safety first position.

These connections are normally arranged to idle or to be ineffective when the press head and the toggle members are out of the safety first position, and are arranged to be moved into effective position, (that is into a position to effectively transmit the power of the power member to the toggle) by the straightening movement of the toggle, effected by the closing of the head 2 by the operator independently of the power mechanism.

The buck 1 is here shown as supported upon a bracket 3, which in turn is mounted on a table 4 forming part of the main frame, the table being supported on suitable legs 5 or pedestals 6. The press head 2 is carried by a lever or yoke 7, pivoted between its ends at 8, to a standard 9 forming an upper extension of the rear leg 6 of the frame.

10 is the counterbalancing weight mounted on the rear arm of the yoke 7, and tending to counterbalance the head 2; and 11 is the spring connected to the rear end of the arm 7, tending to open the press, that is, to actuate the lever 7 to move the head upwardly.

12 is the power member it being here shown as a lever pivoted between its end on a horizontal pivot 13, to the frame near the base thereof, this lever extending forwardly and rearwardly.

14 and 15 are toggle members pivoted together at 16, and pivoted respectively at 17 to the rear arm of the yoke 7 and to the frame, the lever 15 being preferably pivoted to the frame by the pivot 18 that connects the power lever 12 to the frame.

The member 15 is double as shown in Fig. 3, and includes links arranged on opposite sides of the member 14 and the lever 12.

The toggle members, when the head is open, are in the position shown in full lines in Fig. 2, and are movable toward straightened position, but not entirely into straightened position, by the movement of the press head 2 a predetermined distance toward the buck 1, this predetermined distance being preferably sufficient to bring the head close to the buck 1 or the work thereon, so that there is not room for the operator to have his hands or fingers between the head 2 and the work on the

buck. The yoke 7 is provided with a suitable handle 18 for so moving the head to safety-first position.

The connections between the power member or lever 12 and the toggle are arranged to idle or work ineffectively when the press head is open or at any time before the head 2 is brought down to safety-first position and to effectively transmit motion only after the head 2 has been brought down to safety-first position. These connections comprise links one pivotally connected to the toggle, and the other to the rear arm of the power lever, and pivotally connected together by a lost motion connection, a stop for limiting the relative pivotal movement of the link connected to the toggle in the direction of the closing movement of the toggle, and a stop for limiting the relative pivotal movement of such links about their pin and slot connection, when the press head 2 has been brought to a safety-first position, the links at this point being usually in a straight line as shown in Fig. 1, and in dotted lines, Fig. 2.

19 and 20 designate the links respectively, the link 19 being pivoted to the toggle and preferably mounted on the toggle joint or pivot 16 and forming a downward extension of the toggle member 14, the link 19 having a pivotal movement relatively to the toggle member 14, and the toggle member having a stop 21, on its front side. Thus the toggle member 14 and the link 19 are connected together by a stop joint. The link 14 is also provided with a stop 22 for limiting the relative pivotal movement of the link 19 in the direction of the straightening movement of the toggle, and a spring 23 is interposed between the links 14 and 19, or arranged in any other manner to tend to thrust the link 19 toward the stop 21, and resist pivotal movement of the link 19 in a rearward direction.

The link 20 is pivoted at 24 to the rear arm of the power lever 12 and normally extends horizontally rearwardly therefrom, and is pivotally connected to the lower end of the link 19 by a pin and slot connection, the link 19 being formed with a pin 25 working in a lengthwise slot 26 in the link 20. The link 20 is also formed double as shown in Fig. 3, and extends on opposite sides of the link 19, and the opposite sides of the link 20 are connected by a part 27 on the rear or lower side thereof which part acts as a stop to limit the relative pivotal movement of the links 19 and 20 when they have been brought to straightened position as indicated in Fig. 1, and in dotted lines Fig. 2. The link 20 is shorter than the toggle member 15, and hence the links 19 and 20 come into straight position before the toggle members 14 and 15 are in straightened position. Owing to this arrangement, when the press head has been brought down to a safety first position, the links 19 and 20 are brought into effective or operative

position and then when power is applied to depress the lever 12, the motion is transmitted through the straightened links 19 and 20, and then by the final straightening movement of the toggle members 14 and 15, to the head 2. During such final straightening of the toggle members 14 and 15, pressure of the power lever is transferred to the head 2.

In the event the power lever 12 is depressed when the head 2 is open, obviously the link 20 will merely idle owing to the pin and slot connection 25, 26. If the power is turned on at an intermediate point when the press head is between wide open and safety first position this lever 20 will merely idle. If the power is applied to depress the lever 12 when the head is nearly to safety-first position and the links 19, 20 nearly to straightened position any tendency of the link 20 to thrust endwise on the link 19, and hence close the press will cause the link 19 to move rearwardly on its pivot against the spring 23, and unless the operator has his hand on the handle 8 such movement will cause the head to open up easily.

The arrangement of the stops 21, 27, is such that they come into action approximately when the pin 25 reaches the lower end of the slot 26, and until these parts come into this relation the links 19 and 20 are merely idle if the lever 12 is depressed. This idling is effected or permitted when the press head 2 is nearly but not quite in the safety-first position by the rearward pivotal action by the link 19 against the spring 23.

The links 14 and 15 are provided with suitable buffers 28, 29, arranged to engage each other when the press head is open and the parts are in the position shown in Fig. 2.

The lever 12 is depressed by power here shown as a shaft 30 having an eccentric 31 thereon coacting with a face 32 on the lever 12, the shaft being actuated by an electric motor 33 connected to the shaft 30 through suitable gearing and a clutch located in the 110 casing 34.

The construction of the gearing and the clutch forms no part of this invention but forms the subject matter of my pending application Sr. No. 695,247, filed February 26, 1924, and is shown in my Patent No. 1,599,115, issued September 7 1926. It is sufficient to bear in mind that the clutch is a periodic or a half revolution clutch, which is thrown "in" by hand and "out" automatically as each half revolution is completed. Throwing of the clutch "in" causes the shaft 30 to make a half revolution and applies power at which time the power lever 12 and parts actuated thereby enter the position shown in Fig. 1. They will remain in this position as long as desired, whereupon the operator again throws the clutch "in" and the shaft 30 makes another half revolution moving the eccentric 31 into the diametrically opposite position from that

shown in Fig. 1, so that, the counterweight 10 and spring 11 open the press. A suitable spring 35 causes the lever 12 to follow the cam although this spring is unnecessary.

Owing to this mechanism, the dead center or neutral points are eliminated that is, points at which the toggle and link might be in such position as to stall the machine by not moving in either direction or momentarily stall the machine and then suddenly close the machine or suddenly open it with violent shocks. Such stalling causes burning out of fuses and of the motor, and breaking of parts of the machine and is liable to cause the machine to injure the operator. Also this mechanism entirely dispenses with supplemental controls manual or automatic. There is but one control lever, to wit: that by which the clutch is thrown in. Although the operator can apply the power or throw in the clutch at any time, the power is ineffective on the press head unless it has been first brought completely down to a safety-first position.

The throwing on of the power at any time may upset the sequence of the machine, but to restore the sequence it is merely necessary to throw in the clutch for an additional idling operation.

What I claim is:

1. A pressing machine comprising a frame, co-operating pressing elements carried by the frame, and one movable toward and from the other, actuating mechanism for the movable element comprising a power member and motion transmitting connections between said member and the movable element including parts normally out of effective position and arranged to be carried to effective position to apply pressure to the movable element when said element is moved independently of the power member to closed position, said connections comprising a toggle including members, one connected to the movable element and the other to the frame, links pivoted respectively to the power member and to the toggle and connected together by a pivotal lost motion connection, and a stop for limiting the pivotal movement of the link pivoted to the toggle.

2. A pressing machine, comprising a frame, co-operating pressing elements carried by the frame, and one movable toward and from the other, actuating mechanism for the movable element comprising a power member, and motion transmitting connections, arranged to be carried to effective position to apply pressure to the movable element, when said element is moved independently of the power member to closed position, said connections comprising a toggle including members, one connected to the movable element, and the other to the frame, links pivoted to the power member and to the toggle respectively, and connected together by a pivotal lost motion connection, a stop for limiting the

pivotal movement of the link pivoted to the toggle, and means for establishing a rigid connection between the links, when the press head has been moved independently of the power member a predetermined distance toward closed position.

3. A pressing machine, comprising a frame, co-operating pressing elements carried by the frame, one movable toward and from the other, actuating mechanism for the movable element comprising a power member, and motion transmitting connections to be carried into effective position to apply pressure to the movable element, when said element is moved independently of the power member to closed position, said connections comprising a toggle including members connected respectively with the movable element and to the frame, links pivoted respectively to the joint of the toggle, and to the power member, and pivoted together by a lost motion connection, a stop for limiting the pivotal movement of the link pivoted to the toggle about the joint of the toggle, and a spring tending to move said link on its pivot toward the stop.

4. A pressing machine, comprising a frame, co-operating pressing elements carried by the frame, and one movable toward and from the other, actuating mechanism for the movable element comprising a power member, and motion transmitting connections comprising a toggle including members connected respectively with the movable element and to the frame, links pivoted respectively to the joint of the toggle and to the power member, and pivoted together by a lost motion connection, a stop for limiting the pivotal movement of the link pivoted to the toggle about the joint of the toggle, a spring tending to move said link on its pivot toward the stop, the links having means for limiting the pivotal movement thereof about their lost motion connection when said links are in approximately a straight line.

5. A pressing machine comprising a frame, cooperating pressing elements carried by the frame, one movable toward and from the other, and actuating mechanism for the movable element comprising a power lever pivoted to the frame between its ends, and motion transmitting connections comprising a toggle including members pivotally connected respectively to the movable element and to the frame, a link pivoted on the joint of the toggle, and a link pivoted to one arm of the power lever and connected to the former link by a lost motion pivotal connection, and a shoulder on the link pivotally connected to the power lever to limit the pivotal movement of such link in the direction of the closing movement of the toggle.

6. A pressing machine, comprising a frame, cooperating pressing elements carried by the frame, one movable toward and from the other, and actuating mechanism for the mov-

In testimony whereof, I have hereunto signed my name, at Syracuse, in the county of Onondaga, and in the State of New York, this 20th day of May, 1924.

ALBERT B. CLISSON.
